DESIGN FOR A GOBLET OR SIMILAR ARTICLE

Edward B. Bedford and Mary Parker Fleming,
Oneida, N. Y., assignors to Oneida Community,
Limited, Oneida, N. Y., a corporation of New
York

Application October 4, 1934, Serial No. 53,485

Term of patent 7 years

To all whom it may concern:

Be it known that we, Edward B. Bedford and Mary Parker Fleming, citizens of the United States, residing at Oneida, county of Madison, State of New York, have invented a new, original, and ornamental Design for a Goblet or Similar Article, of which the following is a specification, reference being had to the accompanying drawing, forming part thereof, in which—

Figure 1 is a side elevation of a goblet or similar article showing our new design; and

Figure 2 is a cross section taken on the line 2—2 of Figure 1.

The essential feature of the design is the surface ornamentation of the goblet or similar article.

We claim:

The ornamental design for a goblet or similar article as shown and described.

In testimony whereof we have hereunto set our hands.

EDWARD B. BEDFORD.
MARY PARKER FLEMING.
